UNITED STATES PATENT OFFICE

GEORGE H. PERKINS, OF SALEM, MASSACHUSETTS, ASSIGNOR TO THE ESMOND MILLS,
OF ESMOND, RHODE ISLAND, A CORPORATION OF RHODE ISLAND

METHOD OF AND APPARATUS FOR WEAVING

Application filed November 17, 1928. Serial No. 320,153.

This invention pertains to textile manufacture and relates more particularly to a method of and apparatus for weaving patterned textile fabrics, the present method and apparatus being in the nature of an improvement upon the method and apparatus disclosed in the application of George H. Perkins, Serial No. 298,901, filed August 11, 1928.

As more fully described in said application, the usual method of weaving, particularly when applied to the production of long pattern repeats, results in very substantial waste of the woven material incident to the removal of successive cuts from the loom and in preparation for certain finishing processes. In accordance with the disclosure of the aforesaid application provision is made for weaving a length of waste fabric forming less than a full repeat of the pattern at that point in the weaving operation at which the material is to be cut for removal from the loom, thereby producing a short flap at the end of the last full repeat of a cut and a corresponding short flap in advance of the first pattern repeat of the next cut. This is accomplished in the aforesaid disclosure by weaving the pattern backwardly for a distance substantially equal to half the length of the desired piece of waste fabric at the end of the last full repeat of the pattern, and then weaving the pattern forwardly again to the starting point of a new full repeat to complete the piece of waste fabric, the waste fabric thus woven backwardly and forwardly between full repeats providing the necessary material for the desired flap at the ends of the cuts but usually being less in length than a full repeat of the pattern.

For accomplishing this result the aforesaid application discloses the application of the invention to a jacquard pattern mechanism, and provides apparatus for causing the jacquard cards, when desired, to reverse their normal direction of movement until approximately one-half of the desired intermediate waste material has been woven and then again to reverse and move forwardly in the normal direction for the same

distance. While the method and apparatus described in said application are desirable and fully capable of producing the desired results, it is found in practice, particularly when weaving material requiring a large number of jacquard or other pattern elements per linear inch of the woven fabric, that it is not always easy to care for the pattern elements, sometimes several hundred in number, which must be moved backwardly in opposition to their usual direction of travel while weaving the first half of the waste or flap forming section of fabric.

In accordance with the present invention I accomplish the desired result, that is to say the provision of the short intermediate portion of waste material by weaving the pattern (following the last full repeat of the pattern) a very short section, for example four picks in the reverse direction, following this with a like very short section in the forward or normal direction, then again in the reverse direction, and so on alternately until the desired length of material has been produced, the last of said short sections being in the forward direction so that at its completion all is in readiness to proceed in orderly manner with the next full repeat of the pattern.

When using a drop box or other form of shuttle or color changing loom, the reversal of the pattern means, for example the series of jacquard cards, will usually result in the production of fabric in which the normal pattern is indistinct, confused, or even wholly absent, but since the order of warp shedding as determined by the reversely moving pattern elements is inverse to the normal order, I have for convenience in description and illustration referred to the resultant fabric as of reverse pattern, which would be substantially true in the simpler forms of weaving, and I wish it to be understood that wherever I have referred to reversal of the pattern I have particular reference to the order of warp shedding rather than to the specific appearance of the completed fabric.

The preferred mechanism for accomplishing the above result comprises means for

moving a relatively small number of pattern elements such as jacquard cards, first in one direction and then in the other in alternation so long as is necessary for weaving the predetermined portion of waste material, whereupon the pattern elements resume their normal forward movement for production of full pattern repeats. Since the pattern characteristics of the waste section are of no importance, it is necessary, during the alternate forward and reverse operation of the pattern devices, merely to employ a sufficient number of the pattern elements to insure the production of coherent fabric, and for this purpose four pattern elements are usually sufficient, although it is within the scope of the invention to employ a larger or smaller number if permissible or desirable.

In the accompanying drawings certain desirable steps comprised in my novel method of weaving are disclosed by way of example together with apparatus useful in performing said steps, it being understood that the accompanying drawings are merely by way of illustrating the invention, and that they are not to be understood as limiting the invention to the specific arrangement of parts, or to the specific order of steps except as defined by the appended claims.

30 In the drawings,

Fig. 1 is a view indicating diagrammatically the improved method of weaving in accordance with the present invention;

35 Fig. 2 is an edge view illustrating two cuts of fabric produced by the method of Fig. 1 united by a seam preparatory to the finishing operation;

40 Fig. 3 is a view showing the relatively short length of waste material produced by the present process;

45 Fig. 4 is a fragmentary front elevation showing certain parts of a jacquard mechanism of usual type having the present improvements applied thereto;

50 Fig. 5 is a fragmentary end elevation to larger scale looking from the left-hand side of Fig. 4;

55 Fig. 6 is a section to larger scale, substantially on the line 6—6 of Fig. 5;

Fig. 7 is a fragmentary vertical section substantially on the line 7—7 of Fig. 6;

Fig. 8 is a similar section on the line 8—8 of Fig. 6; and

Fig. 9 is a fragmentary vertical section to smaller scale on the line 9—9 of Fig. 6.

60 In accordance with the usual processes of weaving pattern fabrics it is customary, when sufficient material to form a cut has been provided, to weave a section forming a complete repeat of the pattern which is then cut substantially midway its length to permit removal of the first cut of material from the loom. The waste piece of material thus formed at each end of the cut is much too long to serve as an attaching flap in prepar-

ing the material for the finishing operation so that a substantial portion of it must cut away.

70 In accordance with the present invention, as illustrated in Figs. 1 and 2, I produce a series of repeats A, A in usual manner, but at the end *w* of the last repeat of this series, instead of proceeding normally to weave a waste repeat, I reverse the pattern mechanism and cause the loom to weave the pattern backwardly for a predetermined short distance, forming a small section A'. In accordance with the present invention this reverse weaving is of very short duration, for example four picks, whereupon I resume forward weaving, that is to say, normal forward movement of the pattern while weaving another short section A², which likewise comprises but a few picks, for example four.

75 I thus continue weaving a few picks backwardly and then a similar number of picks forwardly until I have produced a length of fabric sufficient to produce a single attaching flap. At this point in the weaving, without interrupting the operation of the pattern mechanism, I may weave in one or more picks of a contrasting color to produce a cut marker C. I then continue in the same manner to weave with alternate reversals another series A' or A² of short sections until I have produced another section of fabric sufficient to form a single attaching flap. The last short section A² of this flap or waste portion of material is woven in the normal forward direction of the pattern so that when the point *y* is reached, which marks the beginning of a new series B of pattern repeats, the pattern mechanism stands in exactly the same position that it did at the point *w* at which the abnormal pattern movement commenced. The loom may now continue to function in normal manner, producing a second series of repeats B, and the first cut of fabric comprising the series A may be removed from the loom by cutting along the line C.

80 In the diagrammatic illustrations of Figs. 1 and 3 I have indicated but a small number of reversals in the piece of waste material and the relative width of the alternating sections making up this piece of waste material is very greatly exaggerated, indicating many more than four picks, but this mode of illustration has been adopted to facilitate the description and in view of the fact that upon the scale selected it would be substantially impossible to show sections of four picks extent.

85 In accordance with the above method the attaching flaps at the end of one cut and at the beginning of the next may be made as short as desired, since the length of such flaps is in no way dependent upon the length of the normal pattern repeat.

90 While I contemplate that the above method may be carried out in various ways and by the

use of various forms of mechanism, and while it is broadly independent of the particular type of pattern mechanism which may be employed, I have here chosen to illustrate mechanism for practicing this process upon a loom provided with jacquard mechanism such as is used in the weaving of blankets and similar materials.

One common form of jacquard mechanism 10 employs two series of jacquard cards which are moved alternately step by step, and while the present invention is of broader utility, I have chosen herein to illustrate one embodiment of the mechanism particularly 15 adapted for use in connection with a jacquard employing two series of cards, although it is equally applicable, by the mere omission of parts, to a jacquard mechanism employing but one series of cards.

Referring more particularly to Figs. 4 and 5, I have illustrated certain parts of the jacquard proper in order to indicate the application of the present mechanism thereto. Thus in Fig. 4 the two series of jacquard cards are indicated respectively at 3 and 4, said series passing around the usual drums 5 and 6. These drums are mounted to turn in journal bearings carried by bars 7 and 8 sliding in suitable guides in the frame and having 20 slotted brackets 9 and 10 respectively which engage drive rollers 11 and 12 carried by vertically sliding rods 13 and 14 respectively. The rods 13 and 14 are reciprocated vertically by means of levers 15 and 16 actuated by cams or other devices usual in the art but not shown. This vertical movement of the rods 13 and 14 is transmitted through the cam slots in the brackets 9 and 10 to the rollers 11 and 12, thus reciprocating the bars 7 and 40 8 in the usual manner.

Each of the drums 5 and 6 is provided at one or both ends with projecting pins 17 and 18 respectively. As here shown each drum is provided with four pins. A forward driving pawl 19, pivotally supported at 20, normally engages successive pins 17 of the drum 5 as the rod 7 is reciprocated so that the drum 5 is turned step by step, thus advancing the series 3 of cards in a normal or forward direction. In the same way a forward driving pawl 19^a, pivoted at 21, normally cooperates with the pins 18 of drum 6 to advance the series 4 of cards in the normal or forward direction.

The novel mechanism forming the subject matter of the present invention comprises a base or frame 22 (Figs. 4 and 5) which may conveniently be mounted upon a beam 23 constituting one of the usual supports for the 50 jacquard mechanism. This base or frame is provided with upstanding brackets 24 and 25 provided with bearings for parallel shafts 26 and 27. The shaft 26 is provided, near its opposite ends, with rearwardly extending arms 28 and 29 respectively. These arms are

slotted at their rear ends for the reception of pins at the lower ends of brackets 30 and 31 respectively which are attached to the lower ends of pawl lifter rods 32 and 33 guided to slide vertically in bearing brackets 32^a, 33^a 70 projecting forwardly from the frame of the jacquard mechanism. The rods 32 and 33 carry pawl lifters 34 and 35 respectively which underlie portions of the pawls 19 and 19^a. In the normal position, during regular weaving, the rods 32 and 33 with the pawl lifters 34 and 35, are in the position indicated in Fig. 5, where they do not interfere with the normal engagement of the pawls 19 and 19^a with the pins of the jacquard drums. 80

In accordance with the present invention I provide reverse driving pawls 36 and 37, pivoted at 38 and 39 respectively, which are adapted under certain conditions to engage the pins of the drums 5 and 6 respectively 85 and to turn the drums in reverse or backward direction. The pawls 36 and 37 are urged upwardly toward operative position by means of springs 40 (Fig. 5) (but one of which is shown), but are normally held down out of operative engagement with the jacquard drums by means of pawl depressing arms 43 projecting rearwardly from collars 42 mounted on the rods 32 and 33 respectively. 90

Referring more particularly to Figs. 4, 5 and 7, the shaft 27 has fixed thereon a ratchet wheel 44, here shown as having eight teeth. A pawl 45 is adapted at times to engage this wheel for turning it, thereby turning the shaft 27. The pawl 45 is mounted upon an 100 arm 46 of a bell crank lever free to turn on the shaft 27 and having a second arm 47 provided with an elongate slot 48 which receives a pin 49 projecting from a bracket 50 secured to the rod 14. Thus the rod 14 reciprocates the arm 46. When the pawl 45 engages the ratchet 44 the ratchet and shaft 27 are turned step by step. 105

The pawl 45 is provided with a lateral pin 51 which, during normal weaving, rests upon an elevated surface 52 of a controlling cam 53 mounted to turn freely on the shaft 27, thus holding the pawl out of engagement with its ratchet wheel. The cam 53 is provided with an actuating arm 55 projecting rearwardly 110 and having a pull rod 56 pivotally attached to its forward end. This pull rod passes down through an opening in the support 22 and is provided with a handle 57 at its lower end within convenient reach of an operator 115 stationed at the front of the loom. A spring 58 tends to lift the rod 56 and thus to hold the arm 55 in the dotted position shown at 55^a (Fig. 8) with the high part 52 of the cam 53 beneath the pin 51 and the pawl 45 out of engagement with the teeth of ratchet wheel 44. 120

The cam 53 is provided with a single retaining tooth 60 normally occupying the position 60^a in Fig. 8. When the cam has been turned to the full line position indicated in Fig. 8, 125 130

this tooth 60 snaps behind a retaining latch 61 carried by a shaft 62 journaled in a bearing sleeve 63 (Figs. 4 and 6) the pawl normally being held in operative or engaging position by means of a weight 64 or an equivalent spring. The shaft 62 is provided with a releasing arm 65 which is adapted at times to be engaged by a pin 66 projecting from the face of a ratchet wheel 67 mounted to turn freely on the shaft 27. This ratchet wheel 67 is turned step by step by means of a pawl 68 mounted on a lever 69 secured to the shaft 26, the pawl being held in engagement with the ratchet wheel by means of a spring 70. Preferably a locking pawl 71, provided with a counterweight 72, is mounted to turn freely on the shaft 26 and engages the ratchet wheel 67 to prevent reverse movement of the latter. A cam 73 (Figs. 6 and 9) is fixedly secured to the shaft 27. This cam comprises a high portion 74 and a low portion 75, each being of substantially a semi-circumference in extent. A roller 76, carried by an arm 77, engages the peripheral surface of the cams 73. The arm 77 is fixedly secured to the shaft 26 and thus as the cam 73 is rotated and the roller 76 alternately engages the high and low portions of the cam, the shaft 26 is rocked first in one direction and then in the other and at each rocking movement in the counter-clockwise direction as viewed in Fig. 7, the pawl 68 above described turns the ratchet wheel 67 a predetermined distance.

Preferably I mount a retaining device, for example a star wheel 78 (Fig. 9) on the shaft 27 to prevent reverse movement of the latter during the retraction of the pawl 45. A roller 79 engages the edge of the star wheel 78, such roller being carried by a bell crank lever 80 turning freely on the shaft 26 and having a spring 81 adapted to hold the roller 79 against the star wheel.

The operation of the above mechanism is substantially as follows, it being assumed that during normal weaving the rods 32 and 33 occupy the positions shown in Figs. 4 and 5 with the pawl lifters 34 and 35 in their lowermost or inoperative positions, with the controlling cam 53 in the dotted line position indicated in Fig. 8 and with the pin 66 to the right of the latch releasing arm 65, as viewed in Fig. 8.

At the end of the series of repeats intended to form a cut of fabric, the operator grasps the handle 57 and pulls down on the rod 56, thus swinging the controlling cam 53 down to the full line position indicated in Fig. 8, permitting the pin 51 to drop from the high part 52 of the controlling cam to the low part 59 thereof. Since the pin 66 does not now engage the arm 65, the latch 61 is free to engage the tooth 60, thus retaining the controlling cam 53 in the position shown in Fig. 8.

As soon as the pin 51 drops onto the low part 59 of the controlling cam, the pawl 45,

which is constantly moving, engages a tooth of the ratchet wheel 44 and thus begins to move the shaft 27 intermittently. Assuming that the roller 76 is at this time at the end of the low part 75 of the cam 73, the movement of the shaft 27 by the pawl 45 and ratchet wheel 44 will cause the roller 76 to ride up onto the high part 74 of the cam 73, thus rocking the shaft 26 and the arms 28 and 29 and lifting the rods 32 and 33. The pawls 19 and 19^a are thus lifted out of engagement with the jacquard drums and the pawls 36 and 37 are permitted to engage the drums. The drums immediately begin to turn in reverse direction, thus weaving a section of fabric A', Fig. 1, in which the pattern is reversed.

Since the ratchet wheel 44 has but eight teeth and since the high portion 74 of the cam 73 is substantially a semi-circumference in length, the roller 76 will run off of the high part 74 at the end of the fourth active movement of the pawl 45. Since this pawl makes a forward movement corresponding to each actuation of the jacquard drums and thus at each pick of the shuttle, it follows that at the end of the fourth pick the shaft 26 will be rocked back to its original position, thus lowering the reverse driving pawls 36 and 37 and causing the forward drive pawls 19 and 19^a to resume operation. The jacquard drums will now be driven forward or in normal direction for four picks, while the roller 76 travels on the low portion 75 of the cam 73, but at the end of the fourth pick in the forward direction the roller 76 again rides up onto the high portion 74 of the cam and the reverse driving pawls are again put into operation. This alternate reverse and forward drive of the pattern mechanism continues for a predetermined period dependent upon the number of teeth in the ratchet wheel 67. At some suitable point in this abnormal operation of the pattern mechanism, provision may be made for weaving in a weft of distinctive color to form a cut marker C, although this is not necessary.

At each rocking movement of the shaft 26 in one direction, the pawl 68 is actuated to move the ratchet wheel 67 forward one step, thus gradually moving the pin 66 until it engages the releasing arm 65. At the next movement of the pawl 68 the pin 66 moves toward the position 66^a and actuates the releasing arm 67 to disengage the latch 61 (Fig. 8) from the tooth 60, thereupon the spring 58 raises the rod 56 and restores the cam 53 to its normal position with its high portion 52 beneath the pin 51, thus holding the pawl 45 in inoperative position. The shafts 27 and 26 thus come to rest with the roll 76 at the end of the low part of the cam 73 and with the pawl lifters 34 and 35 in inoperative position.

Since the jacquard drums are moved rearwardly and then forwardly to the same amount at each reversal of the driving pawls they are left at the end of the above operation in exactly the same position as at the beginning, so that the next card presented for operation by the following movement of the forward driving pawls 19 and 19^a is that which corresponds to the beginning 10 of a new pattern repeat, and the loom mechanism is now ready to proceed in orderly fashion with the production of a new cut of material.

While the mechanism hereinabove described is arranged to weave the waste section of fabric upon four cards only of the jacquard, it is obviously possible by a very slight modification to change the number of cards which take part in the production 20 of the waste fabric, and I contemplate that a greater or lesser number may be employed as circumstances may warrant, it being sufficient merely to change the number of teeth in the ratchet wheel 44 or the extent of the 25 cam surfaces of cam 73 to produce such variation in operation.

Since with the arrangement described but a small number of pattern cards take part in the operation, no substantial difficulty is 30 experienced in guiding and supporting these cards as they are advanced and then reversed, and even though a substantially greater number of cards, for example eight or twelve, were to take part in this operation, no such difficulty would be experienced as where several hundred cards are employed.

While a desirable arrangement of mechanism has herein been illustrated and described, I contemplate that various changes 40 in size and proportion of parts, as well as the substitution of equivalents may be made without departing from the spirit of the invention.

45 I claim:

1. That method of weaving textile fabric having a series of recurrent pattern repeats which comprises as steps weaving a predetermined number of complete repeats, then 50 weaving in succession thereto a series of short sections each of the same number of picks with the same pattern reversed and in the normal direction, alternately, the first such section having the pattern reversed and the 55 last such section having the pattern in normal direction, and then weaving a new series of recurrent pattern repeats.

2. That method of weaving textile fabric having a series of recurrent pattern repeats 60 which comprises as steps weaving a predetermined number of complete repeats, then weaving in a small number of picks with the pattern reversed, the same number of picks in the forward direction, the same number reversed, and so on in alternation until a pre- 65

determined length of waste material has been woven, and then proceeding to weave another series of pattern repeats in orderly fashion.

3. That method of weaving textile fabric having a series of recurrent pattern repeats which comprises as steps weaving a predetermined number of complete repeats, then weaving groups of four picks each with the pattern reversed and in normal direction alternately until a predetermined length of waste material has been woven.

4. That method of weaving by the use of pattern elements in series which comprises as steps weaving in succession a series of lengths of fabric each embodying a complete pattern repeat, and thereafter alternately moving a selected number, substantially less than the full number, of the pattern elements employed in forming said pattern first forwardly and then rearwardly a plurality of times whereby to form successive short sections of waste fabric in which the same pattern extends in normal forward direction and in reverse direction respectively.

5. That method of weaving by the use of warp shedding pattern elements in series which comprises as steps weaving in succession a series of lengths of fabric each embodying a complete pattern repeat, and thereafter alternately moving a relatively small number of the elements employed in forming said pattern forwardly and then rearwardly a plurality of times while weaving a predetermined length of waste fabric, and in immediate succession thereto moving the entire series of pattern elements forwardly while weaving a full pattern repeat.

6. Apparatus of the class described comprising means for weaving in succession a series of lengths of fabric, each length embodying the complete normal pattern which the apparatus is designed to produce, and means for causing the weaving means, at the end of a selected length, to weave a short section of waste material consisting of a series of groups of picks, each of the same number, with the pattern reversed in alternate groups.

7. Apparatus of the class described comprising means for weaving in succession a series of lengths of fabric, each embodying the complete normal pattern which the apparatus is designed to produce, and means for causing the weaving means, at the end of a selected length, to weave four picks forming a portion of the pattern reversed, then four picks with the pattern in normal direction, then four picks reversed, and so on in alternation until a predetermined length of abnormal waste fabric has been woven.

8. Apparatus of the class described comprising means for weaving in succession a series of lengths of material, each length embodying the complete normal pattern which the apparatus is designed to produce, and means for causing the weaving means, at the 130

end of a selected length, to weave a series of successive short lengths of waste fabric in which a portion of the same pattern extends alternately in normal direction and in reverse direction, respectively, and thereafter to resume normal weaving of recurrent complete pattern repeats.

9. Apparatus of the class described comprising means for weaving in succession a series of lengths of material, each length embodying the complete normal pattern which the apparatus is designed to produce, and for causing the weaving means, at the end of a selected length, recurrently to weave a predetermined number of waste picks with the same pattern in normal forward direction and alternately the same number of picks in the reverse direction, and at the end of a predetermined number of such alternations to cease interfering with the normal operation of the pattern means.

10. Apparatus of the class described for use with a loom having weaving instrumentalities and means for actuating them, pattern means for controlling them, and means normally operative to drive the pattern means in a forward direction whereby to weave a series of full pattern repeats, said apparatus comprising means for temporarily taking control of the pattern means and for moving it alternately forward and backward a series of times while weaving a section of fabric less in length than a full pattern repeat.

11. Apparatus of the class described for use with a loom having weaving instrumentalities and means for actuating them, pattern means for controlling them, and means normally operative to drive the pattern means in a forward direction whereby to weave a series of full pattern repeats, said apparatus comprising means for driving the pattern means in reverse direction, control means for causing the forward and reverse drive means to act alternately while weaving a series of short lengths of fabric, and timing means for throwing the control means out of action at the end of a predetermined period of operation.

12. Apparatus of the class described for use with a loom having weaving instrumentalities and means for actuating them, pattern means for controlling them, and means normally operative to drive the pattern means in a normal forward direction whereby to weave a series of full pattern repeats, said apparatus comprising means for driving the pattern means in reverse direction, control means including a cam for selectively determining the operation of the forward and reverse drive means, a pawl for moving the cam whereby alternately to cause the forward and reverse drive means to act, and timing means for rendering the pawl inoperative at the end of a predetermined period of operation.

13. Apparatus of the class described for

use with a loom having weaving instrumentalities and means for actuating them, pattern means for controlling them, a driving pawl normally operative to move the pattern means step by step in a forward direction, said apparatus comprising means for moving the pattern means step by step in a reverse direction, a cam adapted to cause the forward and reverse drive means alternately to operate, a ratchet wheel for driving the cam, a pawl for moving the ratchet wheel step by step, and timing means for determining the length of the period of operation of the pawl.

14. Apparatus of the class described for use with a loom having weaving instrumentalities and means for actuating them, pattern means for controlling them, and means normally operative to drive the pattern means in a forward direction whereby to weave a series of full pattern repeats, said apparatus comprising means for driving the pattern in reverse direction, manually actuatable control means for causing the forward and reverse drive means to act alternately while weaving a like number of picks, and timing means for throwing the control means out of operation at the end of a predetermined series of reversals.

15. Apparatus of the class described for use with a loom having weaving instrumentalities and means for actuating them, pattern means for controlling them, and means normally operative to drive the pattern means in a forward direction whereby to weave normal pattern repeats, said apparatus comprising means for driving the pattern means in reverse direction, control means for causing the forward and reverse drive means to act alternately while weaving a like number of picks, a latch to maintain the control means in operation, and timing means operative after a predetermined series of reversals, to release the latch and thereby permit the control means to cease its function.

16. An attachment for controlling a jacquard mechanism having means normally operative to move a series of pattern cards forward step by step, said attachment comprising reverse drive means, a normally stationary cam having high and low parts adapted to determine alternating periods of operation of the forward and reverse drive means respectively, a ratchet wheel for turning the cam, the number of teeth of the wheel being an even multiple of the sum of the high and low parts of the cam, a normally inactive pawl for actuating the ratchet wheel and means for initiating effective movement of the pawl to turn the ratchet wheel.

17. An attachment for controlling a jacquard mechanism having means normally operative to move a series of pattern cards forward step by step, said attachment comprising reverse drive means, a normally stationary rotary cam having high and low

parts each of substantially equal extent adapted to determine alternate periods of operation of the forward and reverse drive means respectively, a ratchet wheel for driving the cam, the ratchet wheel having an even number of teeth, means for actuating the ratchet, and means operative after a predetermined number of revolutions of the cam to disengage the pawl from the ratchet wheel.

18. Apparatus of the class described for use with a loom having weaving instrumentalities and means for actuating them, pattern means for controlling them, a driving pawl normally operative to move the pattern means step by step in a forward direction, said apparatus comprising means for moving the pattern means step by step in a reverse direction, a normally stationary cam adapted, when moved, to cause the forward and reverse drive means alternately to operate, a ratchet wheel for driving the cam, a pawl for moving the ratchet wheel step by step, a pawl controller operative to hold the pawl out of action during normal weaving, means for moving the pawl controller to inactive position to permit the pawl to operate the ratchet wheel and for temporarily holding the controller in inactive position, and timing means operative to permit the pawl controller to return to normal operative position at the end of a predetermined period.

19. Apparatus of the class described for use with a loom having weaving instrumentalities and means for actuating them, pattern means for controlling them, a driving pawl normally operative to move the pattern means step by step in a forward direction, said apparatus comprising means for moving the pattern means step by step in a reverse direction, a normally stationary cam adapted, when moved, to cause the forward and reverse drive means alternately to operate, a ratchet wheel for driving the cam, a pawl for moving the ratchet wheel step by step, a pawl controller normally operative to hold the pawl out of action during normal weaving, means for moving the pawl controller to inactive position to permit the pawl to operate the ratchet wheel, a latch for temporarily holding the controller in inactive position, and timing means for releasing the latch.

20. An attachment for controlling a jacquard mechanism having means normally operative to move a series of pattern cards forward step by step, said attachment comprising reverse drive means, a normally stationary cam adapted, when moved, to cause the forward and reverse drive means alternately to actuate the cards, and means for turning the cam and for stopping it after a plurality of revolutions.

21. An attachment for controlling a

jacquard mechanism having means normally operative to move a series of pattern cards forward step by step, said attachment comprising reverse drive means, a normally stationary cam adapted when moved to cause alternate operation of the forward and reverse drive means, means for advancing the cam step by step, and retaining means for holding the cam stationary during the intervals between successive advances thereof.

22. An attachment for controlling a jacquard mechanism having means normally operative to move a series of pattern cards forward step by step, said attachment comprising reverse drive means, a normally stationary cam adapted to be rotated and thereby to cause alternate operation of the forward and reverse drive means, pawl and ratchet means for turning the cam step by step, and detent means for preventing reverse movement of the cam when the pawl is retracted.

23. Apparatus for use with a loom having weaving instrumentalities and means for actuating them, pattern means for controlling them, a driving pawl normally operative to move the pattern means step by step in a forward direction, said apparatus comprising means for moving the pattern means step by step in a reverse direction, a cam adapted to cause the forward and reverse means alternately to operate, a ratchet wheel for driving the cam, a pawl for moving the ratchet wheel step by step, a latch for temporarily holding the controller in inactive position, a ratchet wheel, a pawl operative at each shift from reverse to forward drive to advance the ratchet wheel, and a latch releasing pin carried by the ratchet wheel and adapted to release the latch at the end of a predetermined arc of movement of the wheel.

Signed by me at Boston, Massachusetts, this sixteenth day of November, 1928.
